UNITED STATES PATENT OFFICE.

ARTHUR T. PRESCOTT, OF EAST ORANGE, NEW JERSEY, ASSIGNOR TO GEORGE H. FROTHINGHAM COMPANY, OF NEW YORK, N. Y., A CORPORATION OF NEW YORK.

TWO-LIFT DOOR.

1,191,929.

Specification of Letters Patent. Patented July 18, 1916.

Application filed February 21, 1916. Serial No. 79,659.

To all whom it may concern:

Be it known that I, ARTHUR T. PRESCOTT, a citizen of the United States, and a resident of East Orange, county of Essex, and State of New Jersey, have invented certain new and useful Improvements in Two-Lift Doors, of which the following is a specification, reference being had to the accompanying drawings, forming a part thereof.

10 My invention relates to doors and particularly to heavy multi-section doors, such as are adapted for use in warehouses, factories, pier sheds, and for like purposes.

One object of my invention is to provide 15 an improved door of the aforesaid character having a simple and effective operating and counterweight equipment, whereby the weight of the door is substantially balanced in every position while it is being opened 20 and closed.

Other objects and advantages of my invention will be set forth hereinafter, and in order that my invention may be thoroughly understood I will now proceed to describe 25 the same in the following specification and then point out the novel features thereof in appended claims.

Referring to the drawings: Figure 1 is a front elevation of a door, arranged and equipped in accordance with my invention. Fig. 2 is a sectional elevation of the same door taken at right angles to Fig. 1. Fig. 3 corresponds to Fig. 2, except that the door is shown in its open instead of its closed 35 position. Fig. 4 is a plan view of the door in its open position, showing a portion of the counterweight and operating mechanism of a second door adjacent to the first. Fig. 5 is a sectional plan view showing a portion 40 of the two door sections, overlapped and drawn to a larger scale. A modification of my invention is shown in Figs. 6 and 7 which correspond respectively to Figs. 2 and 3. Fig. 8 is a view corresponding to Fig. 5 but 45 taken below the upper section of the door.

In the structure illustrated in Figs. 1 to 5 inclusive, 10 designates a pair of door posts which partially define a plurality of adjacent door openings, the lintel of one of the 50 openings being designated 11. The door shown comprises an upper section 12 which is pivotally suspended from above the door opening as, for example, by hinges 13 and a lower section 14 which is adapted to slide 55 in stationary guideways 14^a provided on the

door posts in a well known manner, and in guideways 15 on the upper section.

Near the lower corners of the upper section 12 are sheaves 16 and shown directly above these are stationary sheaves 17. The 60 sheaves 16 are preferably located near the edge of the door section on which they are mounted and beyond the guideways 15 so that they do not interfere with the sliding movement of the lower section 14. The 65 position of the sheaves 17 may of course be varied without changing the operation of the door.

The operating and counterweight mechanism comprises a shaft 18 on which is mounted a counterweight drum 19, pocket sheaves 20, and a gear wheel 21; a shaft 22 on which are guide sleeves 23, a countershaft 24 carrying a sheave 25 for a hand chain 26, and interposed gears 27 between the gear wheel 21 75 and the countershaft 24.

The main counterweight 28 is suspended by a chain 29 from the counterweight sheave 19 which is specially formed to enable the counterweight to substantially balance the 80 weight of the door in all intermediate positions as it is opened and closed. This feature of my invention will be more fully explained hereinafter.

Suspended from the door hoisting chains 85 30 which extend over the pocket sheaves 20 are auxiliary counterweights 31. The chains 30 extend from the pocket sheaves 20 over sheaves 23, then around sheaves 16, then upward and over the sheaves 17 extending 90 finally downward to the lower corners of the lower door section 14, where they are attached to projections 32.

The shaft 22 and the sheaves 23 are spaced 95 from the plane of the door opening a distance which is about equal to the length of the upper door section. The projections 32, as clearly shown in Fig. 5, are of sufficient length to extend beyond the guideways 15 and into the planes of the sheaves 17 from 100 which the chains 30 extend to the projections. The projections 32 in addition to serving as points of attachment for the chains 30, may also constitute stops and engage the supports for the sheaves 16 when 105 the lower section has been elevated onto the upper section.

Before referring to the modification shown in Figs. 6 and 7, the operation of the door already described, will be discussed. 110

Assuming that the door is closed, as shown in Figs. 1 and 2, if the hand chain is actuated to turn the countershaft 24 and the shaft 18 in one direction, the first result effected will be the upward movement of the lower section 14 in the guideways 14^a 15. During this period the counterweights are called upon to substantially balance the weight of only the lower section. Accordingly, the counterweight sheave 19 from which the principal counterweight 28 is suspended, is provided with a portion 35 of relatively small and substantially uniform diameter, the chain being unwound therefrom during this initial movement of the lower door section.

If the hand chain is further actuated, the upper section 12, together with the lower section 14, is swung on its hinges 13 from its initial position to the position shown in Fig. 3. During this movement the pulley 16 acts as a point of attachment for the chain 30 since the projections 32 engage the supports for the sheaves 16 and no further relative movement of the lower section on the upper section is possible. The pull is therefore exerted directly from the sheave 16 to the sheave 23 and the active weight which must be equalized by the counterweights, obviously increases gradually until the doors reach a substantially horizontal position as shown in Fig. 3. To compensate for this gradual increase in weight and to insure the continued equalization of the weight of the doors, the sheave 19 is provided with a portion 36 which is frusto-conical, so that the effect of the counterweight 28, as the chain is unwound, gradually increases. While for simplicity I have shown the sheave 19 with smooth surfaces, it will usually be provided with a helical groove pocketed to receive the links of the chain 29.

The structure of Figs. 6 and 7, to which reference may now be had, corresponds in most particulars to that already described, and like parts are designated by the same reference characters. The stationary sheaves 17 are, however, replaced by a pair of sheaves or rollers 40 located near the lower corners of the lower section 14. The chains 30 extend over the sheaves 23, as in the previous arrangement; then around the sheaves 16, but instead of extending upwardly over the pulleys 17, they extend downwardly around the pulleys 40 and are attached at their ends to projections 41 on the opposite side from the sheaves 16 and near the lower corners of the upper section 12. This arrangement has the advantage of shortening the chains 30. In operation this structure corresponds to that already described, the arrangement of the door sections, when the door is open, being clearly illustrated in Fig. 7.

Various modifications of the structures

illustrated may be effected within the spirit and scope of my invention, and I intend that only such limitations be imposed as are indicated in the appended claims.

What I claim is:

1. A door comprising an upper section pivotally supported from above, a lower section adapted to slide upon the upper section, a flexible hoisting member adapted to successively raise the lower section upon the upper section and swing the upper section about its pivotal support, and means on the upper section for guiding the flexible member when the lower section is sliding upon the upper, said guide means constituting a point of attachment between the flexible member and the door while the upper section is being swung about its support.

2. A door comprising an upper section pivotally supported from above the door opening and having vertical guideways near its edges, a lower section adapted to slide in the guideways upon the upper section and having projections near its lower corners extending beyond the guideways and adapted to engage the lower end of the guideways when the doors are overlapped, guide pulleys on the upper section near its lower corners, and flexible hoisting members extending over the guide pulleys and attached to the aforesaid projections on the lower sections.

3. A door comprising an upper section pivotally supported from above the door opening and having vertical guideways near its edges, a lower section adapted to slide in the guideways upon the upper section and having projections near its lower corners extending beyond the guideways and adapted to engage the lower end of the guideways when the doors are overlapped, guide pulleys on the upper section near its lower corners, stationary guide sheaves above the door opening, and flexible hoisting members extending over the guide sheaves on the upper section, then over the stationary guide sheaves and secured to the projections of the lower section.

4. A door comprising an upper section pivotally supported from above the door opening and having guideways, a lower section adapted to slide in the guideways on the upper section, stationary guide pulleys above the door pivot, stationary guide pulleys spaced inwardly a distance substantially equal to the length of the pivotally supported door section, a guide pulley near the bottom of the upper section, a counterweight pulley, a counterweight, a flexible member extending from the counterweight over the counterweight pulley, then over the spaced pulley, around the pulley on the upper door section and connected to exert a pull upon the lower section to cause it to slide upward on the upper section and upon

the upper section causing it to swing inwardly about its pivotal support.

5. A door comprising an upper section pivotally suspended from above the door opening and having guideways, a lower section adapted to slide in the guideways on the upper section, stationary guide pulleys above the door pivot, stationary guide pulleys spaced inwardly a distance substantially equal to the length of the pivoted door section, a counterweight pulley, a counterweight, a flexible member extending from the counterweight over the counterweight pulley, then over the spaced pulley, around the pulley on the upper door section, over the stationary pulley above the door pivot and downwardly to connect with the bottom of the lower section.

6. A door comprising an upper section hinged near its upper edge above the door opening and having a guide member near its lower end, a lower section adapted to slide on the upper section and having a guide member near its lower end, a flexible member tending to open the door extending over the guide member on the upper section, under the guide member on the lower section, and connected to the lower end of the upper section.

30 7. A door comprising an upper section hinged near its upper edge above the door opening, a lower section adapted to slide upon the upper section, a guide sheave on the upper section, a guide sheave near the bottom of the lower section, a counterweight mechanism, and a flexible member connecting the counterweight mechanism and extending over the guide pulley of the upper

section, around the guide pulley of the lower section, and connected at its end to the lower end of the upper section.

8. A door comprising an upper section pivotally supported from above the door opening, a lower section adapted to slide upon the upper section, a guide sheave on the upper section, a guide sheave near the bottom of the lower section, a counterweight mechanism comprising a sheave having a cylindrical portion and an adjacent frustoconical portion of increasing diameter, a fixed pulley spaced from the counterweight mechanism in the direction in which the door is adapted to swing, and a flexible member extending from the counterweight mechanism over the fixed pulley around the guide pulley on the upper section, under the guide pulley of the lower section, and connected at its end to the lower end of the upper section.

9. A door comprising an upper door section pivotally supported from above the door opening, a lower section adapted to slide upon the upper section and having a guide member near its lower end, a counterweight mechanism, a fixed pulley spaced from the counterweight mechanism in the direction in which the door swings, and a flexible member extending from the counterweight mechanism, over the fixed pulley, under the guide member of the lower section, and connected at its end to the lower end of the upper section.

In witness whereof, I have hereunto set my hand this 12th day of February, 1916.

ARTHUR T. PRESCOTT.
